(57) **CLAIM**

The ornamental design for an inverter as shown and described herein.

DESCRIPTION

FIG. 1 is a perspective of an inverter showing the new design;

FIG. 2 is a front view thereof;

FIG. 3 is a rear view thereof;

FIG. 4 is a left-side view thereof;

FIG. 5 is a right-side view thereof;

FIG. 6 is a top plan view thereof; and,

FIG. 7 is a bottom plan view thereof.

The broken lines in the drawings depict portions of the inverter that form no part of the claimed design.
